UNITED STATES PATENT OFFICE.

WILLIAM L. WALKER, OF NEW YORK, N. Y.

VAULT-LIGHT.

1,258,066.

Specification of Letters Patent.

Patented Mar. 5, 1918.

Application filed November 15, 1916. Serial No. 131,539.

To all whom it may concern:

Be it known that I, WILLIAM L. WALKER, a citizen of the United States, and resident of New York, in the county of New York and State of New York, have invented new and useful Improvements in Vault-Lights, of which the following is a specification.

This invention relates to lights of the general type comprising essentially a plurality of lenses suitably secured within a frame, such as are commonly used for lighting vaults, basements, cellars and the like. Its principal object is to provide a lens which can be readily and securely installed with an air tight and water tight joint between it and the frame and at the same time is readily removable as the lenses become chipped or broken in service.

Referring to the drawings which illustrate certain embodiments of my invention,

Figure 1 is a vertical central section of my improved lens and frame;

Fig. 2 is a similar view of a modified form;

Fig. 3 is a bottom plan view of the lens shown in Figs. 1 and 2;

Figs. 4 and 6 are vertical central sections of other modified forms;

Fig. 5 is a section on the line 5—5 Fig. 4; and

Fig. 7 is a perspective view of the fastening bolt shown in Fig. 4.

Referring to Fig. 1, A is a cast iron frame and jacket of usual construction but having in addition a shoulder or seat A' and a tapering inner wall above said seat. B is the lens, T-shaped in cross section, adapted to rest on the seat A' and provided with a T-shaped slot B' adapted to receive a headed fastening bolt C. At and near its top the lens is formed with a taper corresponding to the taper of the inner wall of the jacket A. Preferably a washer or cushion D of rubber, or similar compressible material, is held between the lens and the head of the bolt C. A bushing E of rubber or other suitable compressible material is held between the tapered portions of the lens and jacket and extends from the top of the jacket over the seat A'.

F is a metal rod extending across and engaging the bottom of the jacket and having an aperture to permit the passage therethrough of the threaded end of the bolt C which has a nut G.

It will I believe be clear that when the nut G is tightened, the lens B is drawn down on to its seat A' compressing the bushing E and forming a water and air tight joint between the lens and the jacket. In the event of breakage of the lens it is necessary merely to unscrew the nut G which permits the broken lens to be readily removed and replaced.

Referring now to Fig. 2, the frame and jacket instead of being integral as in Fig. 1, comprise a metal support A², preferably of punched steel, having an integral, turned down, screw-threaded lip A³ to which is secured the metal jacket A⁴ having a flange a which rests upon the top of the frame. The inner wall of the jacket A⁴ is tapered throughout its entire length and the lens B has a corresponding taper. The compressible bushing E extends substantially from top to bottom of the lens and said lens is drawn into place and secured in the same manner as in the construction shown in Fig. 1.

In the form of my invention shown in Figs. 4 and 5 T-shaped slots B² and grooves B³ are provided on opposite sides of the lens B adapted to receive the T-shaped bolts C² (Fig. 7), and the jacket A⁵ is provided with inturned lugs A⁶ having slots A⁷ (Fig. 5) to permit the passage therethrough of the threaded ends of the bolts C² provided with the nuts G' for securing the lens in operative position.

The construction shown in Fig. 6 is the same as that shown in Figs. 4 and 5 except that the fastening bolts C³ are wire rods having an elbow or bend at the top forming a head adapted to fit within apertures or slots B⁴ on opposite sides of the lens.

The construction above described is simple, and provides efficient means for securing the lens and for its removal in case of breakage. The compressible rubber bushing between the lens and jacket not only provides an air and water tight joint, but also takes up the expansion and contraction of the metal frame and jacket; furthermore, as the bushing is substantially flush with the top of the jacket it tends to prevent slipping, this fact being of considerable importance where the device according to common practice is used as a basement light set in sidewalks.

I claim:

1. A device of the class described, com-

prising a lens having a recess therein, a jacket, a compressible bushing between said lens and jacket, and means comprising an elongate fastener fitting into said recess at one end and connected at the other end to the jacket, to secure said lens within said jacket with said bushing compressed therebetween.

2. A device of the class described, comprising a lens having a slot, a jacket, a compressible bushing between said lens and jacket, and means comprising a detached fastener having one end in said lens slot and connected at the other end to said jacket to secure said lens within said jacket with said bushing compressed therebetween.

3. A device of the class described, comprising a lens having a recess therein, a jacket, a compressible bushing between said lens and jacket, and means comprising an elongate fastener fitting into said recess at one end and connected at the other end to the jacket, to secure said lens within said jacket with said bushing compressed therebetween, the said means being connected to the lens at a point below the top thereof.

4. A device of the class described comprising a tapered lens having a slot, a jacket having a tapered inner wall, a compressible bushing between said lens and said jacket, and means to hold said lens within said jacket with said bushing compressed therebetween, comprising a fastener having a head adapted to rest within the slot in said lens.

5. A device of the class described com-

prising a tapered lens having a slot, a jacket having a tapered inner wall and a bolt aperture, a compressible bushing between said lens and said jacket, and means to hold said lens within said jacket with said bushing compressed therebetween comprising a bolt adapted to pass through said bolt aperture and having a head adapted to rest within said slot in said lens.

6. A device of the class described comprising a tapered lens having a slot, a jacket having a tapered inner wall and a lug provided with a bolt aperture, a compressible bushing between said lens and said jacket, and means to hold said lens within said jacket with said bushing compressed therebetween, comprising a bolt adapted to pass through said bolt aperture and having a head adapted to rest within said slot in said lens.

7. A device of the character described comprising a tapered lens, a jacket having a tapered inner wall, a compressible packing between said lens and said jacket, and means comprising a bolt connected directly to the lens at one end and arranged to force the lens directly into the jacket, thereby to compress the packing tightly between the lens and the jacket.

Signed by me at New York, N. Y., this sixth (6th) day of November, 1916.

WILLIAM L. WALKER.
